[57] **CLAIM**

The ornamental design for a front bezel for a floor-standing personal computer, as shown and described.

DESCRIPTION

FIG. 1 is a top front and right side perspective view of a front bezel for a floor standing personal computer incorporating a design according to the invention;

FIG. 2 is a rear elevation of the front bezel of FIG. 1;

FIG. 3 is a left-side elevation of the front bezel of FIG. 1;

FIG. 4 is a sectional view of the front bezel of FIG. 1, taken along line 4—4 in FIG. 2;

FIG. 5 is a bottom plan of the front bezel of FIG. 1; and, FIG. 6 is a perspective partial view of a personal computer including the front bezel of FIG. 1.

The broken lines in FIG. 6 are shown for illustrative purposes only, and form no part of the claimed design.
